(57) **CLAIM**

The ornamental design for a skater's support, as shown.

DESCRIPTION

FIG. 1 is a perspective view of a skater's support showing my design, taken from in front and to one side, looking down obliquely;

FIG. 2 is a top plan view thereof;

FIG. 3 is a side elevational view thereof, the elevational view from the other side being a mirror image;

FIG. 4 is a front end view thereof; and,

FIG. 5 is a rear elevational view thereof.
